UNITED STATES PATENT OFFICE.

JOHN W. BURGESS, OF KANSAS CITY, MISSOURI.

GARMENT.

1,410,648.

Specification of Letters Patent. Patented Mar. 28, 1922.

Application filed January 19, 1920. Serial No. 352,275.

To all whom it may concern:

Be it known that I, JOHN W. BURGESS, a citizen of the United States, residing at Kansas City, in the county of Jackson and 5 State of Missouri, have invented a new and useful Garment, of which the following is a specification.

The device forming the subject matter of this application is a garment, and the 10 invention aims to provide a garment embodying an ulster closed or open in the back, a jacket with or without trousers, a pair of trousers with or without a belt, a skirt with or without a belt, an apron with a belt, 15 and a jacket having an apron.

It is within the province of the invention to improve generally and to enhance the utility of devices of that type to which the invention appertains.

20 With the above and other objects in view, the invention consists in the novel construction and arrangement of parts herein-after described, claimed, and shown in the drawings, it being understood that, within 25 the scope of what is claimed, a garment maker or bushelman may make changes without departing from the spirit of the invention.

The garment is shown in the drawings in 30 a single figure, laid flat, parts thereof being separated.

The garment forming the subject matter of this application includes a jacket 1 provided with sleeves 2, over which cuffs 3 may 35 be slipped, the cuffs extending approximately to the elbows. Buttons 4 are mounted on the lower ends of the sleeves 2 and cooperate with button holes 5 in the cuffs 3, the upper ends of the cuffs 3 being provided 40 with resilient bands 6 adapted to hold the upper ends of the cuffs in place on the arms of the wearer. The cuffs 3 may be employed when added warmth is desired, or when the wearer is engaged in dirty work, it being 45 obvious that the cuffs 3 may be removed readily for washing.

One of the longitudinal edges of the jacket 1 is supplied with buttons 7 adapted to cooperate with button holes 8 on the other 50 longitudinal edge of the jacket. Adjacent to its lower edge, the jacket 1 is supplied with loops 9.

The invention comprises a pair of flaps 10, the inner edges of which may be connected by stitching or otherwise, as shown 55 at 11, adjacent to the upper portions of the

flaps. One of the flaps 10 is provided, adjacent to its outer edge, with button holes 17 adapted to cooperate with buttons 18 located upon the other flap, adjacent to the 60 outer edge thereof. One flap 10 is provided upon its inner edge with button holes 19 adapted to cooperate with buttons 20 located on the other flap, near to the inner edge thereof. In the upper edges of the 65 flaps 10, button holes 12 are fashioned, the same being adapted to coact with buttons 14, located on the jacket 1 near to the lower edge thereof. Along their upper edges, the flaps 10 are equipped with loops 15 through 70 which a belt 16 may be passed.

In the foregoing description, buttons and button holes have been alluded to frequently, but it is to be understood that any equivalent for buttons and button holes may 75 be used. A person skilled in the making of garments will appreciate the fact that, if desired, separable snap fasteners or the like, may be used, wherever desired, in the place of buttons and button holes. 80

Let it be supposed that the flaps 10 are connected by the buttons 14 to the lower edge of the jacket 1 and that the buttons 20 are engaged with the button holes 19. Then, the garment may be buttoned up 85 along the front, by means of the buttons 7 and the button holes 8, and through the instrumentality of the buttons 18 and the button holes 17. Under such circumstances, the garment will constitute an ulster, closed 90 in the back. The buttons 20 may be disengaged from the button holes 19, whereupon the garment will appear as an ulster open or slit upwardly in the back.

The buttons 20 may be engaged with the 95 button holes 17, the buttons 18 being engaged with the button holes 19, and the flaps 10 remaining assembled with the jacket 1. Then the garment takes the form of a jacket provided with a pair of trousers. If the 100 flaps 10 are detached from the buttons 14, then the jacket may be used alone, without the trousers formed by the flaps 10 and, of course, the trousers, formed as above described, may be employed without the jacket 105 1. The belt 16 may be used or omitted, as desired, in connection with the trousers. If the belt 16 is used in connection with the loops 9 of the jacket 1, the jacket may be belted in at the waist. 110

The flaps 10 may be detached from the jacket 1, the buttons 20 being engaged with

the button holes 19, and the buttons 18 being engaged with the button holes 17. Then, the flaps 10 constitute a skirt.

The flaps 10 may be detached from the jacket 1, the buttons 20 being engaged with the button holes 19. Then there is provided an apron, which may be held on the body of the wearer by the belt 16. The apron may be employed either in connection with the jacket 1, or without the jacket 1.

Having thus described the invention, what is claimed is:—

In a garment of the class described, a jacket; a pair of flaps having free longitudinal front and rear edges; means for releasably connecting the rear edge of one flap with the rear edge of the other flap and means for releasably connecting the front edge of one flap with the front edge of the other flap whereby the flaps will form a skirt for the jacket, said means be-

ing effective for releasably connecting the rear edge of each flap with the front edge of the same flap whereby the flaps will form a pair of breeches for the jacket; separable fastening elements connecting the upper edges of the flaps to the jacket; loops on the flaps adjacent to the upper edges of the flaps; and a belt received in the loops, the belt covering the fastening elements and forming a constricting means for the garment when the flaps are assembled with the jacket, the belt constituting a supporting means for the flaps alone, when the flaps are separated from the jacket, thereby enabling the flaps to be employed as an apron.

In testimony that I claim the foregoing as my own, I have hereto affixed my signature in the presence of two witnesses.

JOHN W. BURGESS.
